UNITED STATES PATENT OFFICE.

MERRITT W. MAGANN, OF ST. LOUIS, MISSOURI, ASSIGNOR TO ST. LOUIS STEEL BALL CORPORATION, OF ST. LOUIS, MISSOURI, A CORPORATION OF MISSOURI.

BALL-FORMING MACHINE.

Application filed August 31, 1925. Serial No. 53,556.

My invention relates to ball forming machines, and more particularly to a machine for the manufacture of solid metallic balls by a rolling process from hot non-spherical 5 slugs each having a volume of material equal to the volume of material of each finished ball.

The invention is a distinct and practical improvement to overcome certain practical 10 objections to, and defects in, machines for forming solid metallic balls from non-spherical slugs or stock by the continuous rolling movement of hot non-spherical shaped slugs into ball formation, and which balls are 15 adapted for use in grinding cement during the manufacture thereof.

An object of my present invention, which is an improvement over my co-pending application bearing Serial Number 667,895, is to 20 provide a ball forming machine having a plurality of opposed ball forming dies, one member of each die being stationary and its co-acting member being rotatable.

A further object of the invention is to provide 25 two stationary die members each provided with two orbital die grooves, arranged to form an inner and an outer groove concentrically arranged with the faces of each groove provided with spirally shaped cuts or depressions.

A further object of the invention is to provide the orbital die grooves of the two stationary die members with stops and a plurality of groove connecting passages so as 35 to direct the travel of the hot slugs being formed into balls from the outer die groove of the first die to the outer die groove of the opposed, or second die; then, from the outer die groove of the second die to the inner die 40 groove of the first die; then from the inner die groove of the first die to the inner die groove of the second die; and, finally from the inner die groove of the first die to an inclined exit ball passage formed between 45 and in the inner faces of the opposed stationary die members and a peripheral groove of a driven shaft.

A further object of the invention is to provide 50 a coacting rotatable die member for each stationary die member and each having an inner and an outer orbital die groove concentrically arranged to mate with their respective die grooves of the stationary die members, the groove of the rotatable die mem-

bers also being provided with spirally shaped 55 segmental cuts or depressions, which when in register with the spiral cuts or depressions of the stationary die members, form true spiral grooves in the faces of the ball forming die grooves of the assembled die members to 60 facilitate the rolling action of slugs being rolled into ball formation which slugs are under great frictional pressure between the stationary and rotatable die members.

A still further object of my invention is 65 to provide a novel solid ball forming machine, especially adapted for making cement grinding balls, but not necessarily limited thereto, which will possess advantages in 70 points of simplicity, efficiency, durability, and, at the same time prove itself comparatively inexpensive in manufacture, as well as the balls made thereby.

With the above and other objects in view, 75 the invention consists in the novel features of construction, arrangement and combination of parts hereinafter more fully described and finally pointed out in the claims hereto appended.

This invention is but a unit of an apparatus 80 of a method and process I have conceived in the manufacture of solid metallic balls from slugs cut from cold bar stock, then heated and fed to the forming machine for shaping at the desired temperature.

Referring to the accompanying drawings forming a part of this specification, wherein like characters of reference denote similar parts throughout the several views:

Fig. 1, is a top plan view of a ball forming 90 machine embodying the features of my invention.

Fig. 2, is a top plan view thereof with certain parts removed and others broken away to illustrate the ball forming grooves 95 and connecting passages.

Fig. 3, is a vertical sectional view of the machine taken on line 3—3 of Fig. 1.

Fig. 4, is a vertical sectional view of the machine taken on line 4—4 of Fig. 1.

Fig. 5, is an inside elevation of one of the 100 stationary die plates.

Fig. 6, is an inside elevation of the other stationary die plate.

Fig. 7, is an outside elevation of the stationary die plate shown in Fig. 6.

Fig. 8, is an outside elevation of the stationary die plate shown in Fig. 5.

Fig. 9, is an inside elevation of the rotatable die plate coacting with the stationary die plate shown in Fig. 7.

Fig. 10, is an inside elevation of the rotatable die plate coacting with the stationary die plate shown in Fig. 6.

In carrying out the aim of my present invention, which is illustrated in the accompanying drawings, I employ a suitable base 1 which is provided with the opposed standards 2, each of which standards is provided at its upper end with a suitable bearing 3 and a bearing 4. The base 1 can be secured to a suitable foundation by any well known means, such as suitable anchoring or fastening devices, 5, commonly used for such purpose.

A suitable power, or drive shaft 6 is journaled in the bearings 3. One end of the shaft 6 is provided with a suitable fixed pinion 7 adapted to mesh with a suitable gear 8 fixed to one end of a suitable driven shaft 9, which driven shaft 9 is journaled in the bearings 4. The power, or drive shaft 6 is provided with a suitable combined fly wheel and pulley 10 over which rides a suitable belt 11 driven by an electric motor, gas engine, or other suitable source of power, not shown, as is manifest.

The driven shaft 9 is provided intermediate its ends, at a suitable point, with a peripheral flange 12, which flange is provided with a suitable peripheral groove 13. The drive shaft is further provided with a longitudinally disposed cold water passage 14, which passage 14 is enlarged adjacent the peripheral groove 13 to form a water chamber 15 within the flanged section 12, for supplying a sufficient chamber of cold water at this point for cooling the shaft adjacent the ball forming dies to be hereinafter described.

40 The ball rolling mechanism proper will now be described and comprises a pair of suitable rectangular stationary die plates designated 16 and 17. Each die plate is provided with a central opening 18 for the reception of the flange 12 of the driven shaft 9 on which they are mounted, as clearly shown in Fig. 4.

The stationary die plates 16 and 17 are arranged side by side and are seated upon the base 1, as shown in Figs. 1, 2 and 4. These die plates 16 and 17 are held in proper position with relation to each other, such as spreading displacement, by means of suitable corner tie rods 19 passing through the corners of the die plates, and through the corners of two opposite stationary frame plates 20. Suitable sleeves 21 are mounted upon the rods 19 and disposed between each corner of each die plate and its respective frame plate 20, as clearly shown in Figs. 1, 2 and 4. The stationary frame plates 20 are provided with central openings 22 for the passage of the driven shaft 9 and engage both the base 1 upon which they rest and the standards 2, as shown in Figs. 2 and 4.

65 The outer faces of the stationary die plate

16 is provided with an outer concave orbital die groove 23, semi-circular in cross section, which is provided with a gradually enlarged inclined entrance, or feed end 24 for feeding red hot metallic slugs 25 into the machine. The die groove 23 terminates at a stop 26 which is short of the entrance end 24 and does not communicate therewith, as clearly shown in Fig. 3. The die plate 16 is also provided in its outer face with an inner concaved orbital die groove 27, which groove is also semi-circular in cross section and is arranged concentric with the die groove 23. The die groove 27 terminates at the stop 28 which spaces the exit end thereof from the entrance end of the same groove.

The outer face of the stationary die plate 17 is provided with an outer concaved orbital die groove 29, semi-circular in cross section and which die groove 29 is of the same diameter as the outer die groove 23 of die plate 16. The ball exit end of the die groove 29 as indicated by arrow is spaced a suitable distance from the entrance end of the same groove, also indicated by arrow, by means of suitable stop 30. The die plate 17 is further provided in its outer face with an inner concaved orbital die groove 31 which is also semi-circular in cross section, and which is arranged concentric with the outer die groove 29. The die groove 31 is of the same diameter as the opposed inner die groove 27 of die plate 16. The ball exit end of the die groove 31 indicated by arrow, is spaced a suitable distance from the ball entrance end of the same groove, also indicated by arrow, by means of a suitable stop 32.

The reference numerals 33 and 34 represent coacting die plates which are fixed to the flange 12 of the driven shaft 9 by means of suitable fastening devices 35 so as to rotate therewith.

The rotatable die plate 33 is disposed opposite the outer face of the stationary die 16 and is provided with the concentrically arranged outer and inner concaved orbital die grooves 36 and 37, which grooves are adapted to register with the grooves 23 and 27, respectively, of die plate 16, so as to provide the outer and inner orbital ball rolling channels 38 and 39, respectively. The opposed faces of the coacting die plates 16 and 33 are spaced a suitable distance apart so as to provide a scale discharge passage 40 between the die plates 16 and 33.

The rotatable die plate 34 is disposed opposite the outer face of the stationary die plate 17 and is provided with the concentrically arranged outer and inner concaved orbital die grooves 41 and 42 which are adapted to register with the die grooves 29 and 31, respectively of die plate 17, so as to provide the outer and inner orbital ball rolling channels 43 and 44, respectively.

In order to permit the hot slugs to be rolled

into ball formation to pass from one set of ball rolling channels of the dies to the other and vice-versa, I provide the stationary die plates 16 and 17 with registered openings to 5 provide the inclined ball passing channel 45 between the ball outlet end of the ball rolling channel 38 and the ball inlet end of ball rolling channel 43. The stationary die plates 16 and 17 are further provided with registered 10 openings to provide the inclined ball passing channel 46 between the ball outlet end of the outer ball rolling channel 43 and the ball inlet end of ball rolling channel 39. The stationary die plates 16 and 17 are each further 15 provided with registered openings to provide the inclined ball passing channel 47 between the ball outlet end of the inner ball rolling channel 39 and the inlet end of the inner ball rolling channel 44. The stationary die plate 20 17 is still further provided with an opening to provide an inclined ball passing channel 48, which channel communicates with the inner end of a ball discharge channel 49 formed between the die plates 16 and 17 by the inclined opposed concaved grooves 50 and 51 formed in the inner faces of the stationary 25 die plates 16 and 17, as shown in Fig. 2.

The faces of the orbital die grooves are each provided with the spirally cut grooves, 30 or depressions, as described, to provide the orbital ball rolling channels 38, 39, 43 and 44 with so-called "rifles" to assist in the rolling action or movement of the hot slugs during their formation into spherical balls.

35 The peripheral groove 13 of the driven shaft 9 assists in the discharge of the finished balls through the discharge passage or channel 49 due to the rotation of the driven shaft 9 which has a tendency to encourage discharge movement to the finished balls after 40 the balls have been formed between the two sets of die plates.

The stationary die plates 16 and 17 preferably have their inner faces slightly bowed, 45 or dished, as shown in Figs. 1 and 4.

The operation of the machine is as follows:

The hot slugs of metallic stock designated 50 25 are fed into the groove 24 of the stationary die plate 16 and into the outer orbital raceway 38 at the bottom thereof and discharged therefrom and into the outer orbital raceway 43 through the connecting passage 45, as will be apparent from Figs. 2 and 3. The 55 slugs are rolled over the outer orbital raceway 43 and discharged therefrom and into the inner orbital raceway 39 through the connecting passage 46. The balls are then rolled over the inner orbital raceway 39 and discharged therefrom through the connecting passage 47. The balls are rolled over the inner orbital raceway and finally discharged 60 into the discharge passage 49 through the connecting passage 48, as will also be apparent from Figs. 2 and 3.

It will be apparent from the foregoing description and the drawings that the directly opposed die groove of the stationary and rotatable die grooved plates are designed to form an inner and an outer orbital ball 70 forming raceway concentrically arranged between the stationary and the rotatable plates, that the plurality of connecting passages in the stationary die plates are for the purpose of directing balls in formation from the outer orbital raceway of one pair of cooperating die grooved plates to the outer orbital raceway of the other pair of cooperating die grooved plates, from this latter groove to the inner orbital raceway of the 80 first mentioned pair of cooperating die grooved plates and finally from said inner orbital raceway to the inner orbital raceway of the second mentioned pair of die grooved plates from which raceway the balls are discharged into an inclined exit passage formed by inner facial grooves of the stationary die plates assisted in their discharge movement by contact with a peripheral groove of a drive shaft to which the rotatable die 85 grooved plates are fixed.

The many advantages of the herein described invention will readily suggest themselves to those skilled in the art to which it appertains.

I do not desire to be understood as having limited myself to the exact details of construction shown and described, but desire to have it understood that the invention I have shown in the drawings is merely illustrative, as it is 100 manifest that various minor changes may be made in the exact construction and particular arrangement of parts without departing from the spirit of my invention, hence I reserve the right to make any such changes, or 105 modifications, as may fairly fall within the scope of the appended claims when fairly construed.

What I claim is:

1. In a solid metallic ball forming machine 110 structure, a driven shaft, two pairs of concentrically grooved die plates, the outer plates of each pair being mounted for rotation with said shaft and means to allow balls to cross over from the die grooves of one pair of plates to the die grooves of the other pair of plates and vice versa during the process of forming the balls.

2. In a solid metallic ball forming machine 115 structure, a driven shaft, two pairs of concentrically grooved die plates, the outer plates of each pair being mounted for rotation with said shaft and the inner plates of each pair being stationary, means to allow balls to pass from the die grooves of one pair of plates to the die grooves of the other pair of plates and vice versa during the process of forming the balls and a discharge passage 120 formed between the two stationary plates for the exit of the finished balls.

3. In a solid metallic ball forming machine structure, a driven shaft, two pairs of concentrically grooved disc plates, the outer plates of each pair being mounted for rotation with said shaft and the inner plates of each pair being stationary, a feed passage leading to one of the die grooves between one of the rotating plates and its associated stationary plate, means to allow balls being formed to pass from the die grooves of one pair of plates to the die grooves of the other pair of plates and vice versa during the formation of the balls by rolling action between said plates and a discharge passage formed between the two stationary plates for the exit of finished balls.

4. In a solid metallic ball forming machine structure, a driven shaft, a pair of stationary concentrically grooved die plates, a pair of rotatable cooperating concentrically grooved die plates fixed to said shaft, passages directed through the stationary die plates for connecting the like grooves therein, a hot slug feed passage communicating with one set of grooves between one of the rotating plates and one of the stationary plates and an inclined discharge passage formed in the opposed faces of the stationary die plates for the exit of finished balls.

5. In a solid metallic ball forming machine structure, a driven shaft, a pair of stationary plates having slightly dished inner faces to allow metallic chips and scale to be discharged between said plates, means to prevent spreading of said plates, a pair of plates fixed to revolve with said driven shaft, an outer raceway formed by opposed facial die grooves in the inner faces of each pair of stationary and revoluble die plates, a passage in the stationary die plates connecting said outer raceways, an inner circular raceway concentric with the outer raceways formed by opposed facial grooves of each pair of stationary and revoluble die plates, a passage in the stationary die plates connecting the outer raceway of one pair of stationary and revoluble die plates with the inner raceway of the other pair of stationary and revoluble die plates, a passage in the stationary die plates connecting said inner raceway of the latter stationary and revoluble die plates with the inner raceway of the other stationary and revoluble die plates, a passage in the stationary die plates connecting said latter inner raceway with the inner raceway of the other stationary and revoluble die plates, an exit passage formed by opposed facial grooves in the inner faces of the stationary die plates and a passage in one of the stationary die plates connecting the latter inner raceway with the discharge passage.

6. In a machine for forming solid balls from hot metallic slugs, two pairs of opposed ball forming dies, each pair of dies hav-

ing two concentrically arranged raceways, 65 said two pairs of dies having passages communicating with the raceways of each other for transmitting the hot metallic slugs being formed into balls from one of the raceways in one pair of dies to a like raceway in the 70 other pair of dies, then from said latter raceway to the other raceway of the other pair of dies from which raceway it is transmitted to a like raceway in the other pair of dies and from which latter raceway the finished 75 balls are discharged from between said two pairs of dies.

7. In a machine for forming solid metallic balls from hot non-spherical slugs, two pairs of opposed sets of ball forming dies each 80 having a pair of outer and inner raceways concentrically arranged, a slug inlet passage to the outer raceway of one pair of said dies, said pairs of dies having internal passages connecting the concentric raceways of both 85 pairs of dies for transmitting the metal being formed into balls from one pair of dies to the other pair of dies and an outlet passage formed between the two pairs of dies for the discharge of the finished balls. 90

8. In a solid metallic ball forming machine, a pair of opposed stationary concentrically grooved die plates, a cooperating pair of concentrically grooved rotatable die plates and a plurality of internal connecting passages 95 in said stationary plates to cause the balls being formed to first travel between one stationary plate and its cooperating rotary plate and then between the other stationary plate and its cooperating rotary plate and vice 100 versa until the ball is completely formed.

9. In a solid metallic ball forming machine, two pairs of stock forming devices arranged side by side, each pair of devices having a pair of concentrically arranged 105 orbital raceways and a plurality of internal passages connecting the raceways of each pair of stock forming devices.

10. In a solid metallic ball forming machine, two pairs of stock forming devices arranged side by side, each pair of devices having a pair of concentrically arranged orbital raceways, a plurality of internal passages connecting the raceways of each pair of devices, a stock feed passage leading to one 115 pair of said devices and a ball discharge passage formed between both pairs of devices.

11. In a solid ball forming machine structure, a base, a pair of standards for said base, bearings at the upper ends of said standards, a drive shaft, a hollow water cooled driven shaft, gearing connecting said shafts, a peripheral grooved flange for said driven shaft, a pair of stationary die plates through 120 which the driven shaft passes, means to prevent lateral displacement of the stationary die plates, said stationary die plates having 125

slightly dished inner faces to permit metallic
shells gathered therebetween to be discharged
from therebetween, a pair of rotatable die
plates fixed to the flange of said shaft for ro-
tation therewith, an inner and an outer facial
groove concentrically arranged in the inner
faces of each pair of cooperating stationary
and rotatable die plates to form a pair of con-
centric orbital raceways for each pair of co-
operating stationary and rotatable die plates,
internal passages in the stationary die plates
for connecting the raceways of one pair of
cooperating stationary and rotatable die
plates with the raceways of the other pair of
cooperating stationary and rotatable die plates,
a feed groove leading to one of the
other raceways between one pair of cooperat-
ing stationary and rotatable die plates, a dis-
charge passage formed between the two sta-
tionary die plates and a passage in one of the
stationary die plates connecting the inner
raceway thereof with the discharge passage

which discharge passage cooperates with the
peripheral groove of the driven shaft.

12. In a machine for forming solid balls 25
from hot metallic slugs, two pairs of ball
forming dies arranged side by side, each pair
of dies having an outer circular raceway and
an inner circular raceway, a passage leading
from the outer raceway of one pair of dies to 30
the outer raceway of the other pair of dies, a
passage leading from the latter raceway to the
inner raceway of the first mentioned pair of
dies, a passage leading from the latter race-
way to the inner raceway of the second men- 35
tioned pair of dies, a discharge passage be-
tween the two pairs of dies and a passage
leading from the inner raceway of the second
mentioned pair of dies to the discharge pas- 40
sage between the two pairs of dies.

In testimony whereof, I have hereunto
signed my name to the specification.

MERRITT W. MAGANN.
